PUSHBUTTON ELECTRIC SWITCH

Andrew F. Kay, Del Mar, Calif., assignor to Switchpack
Systems, Inc., Solana Beach, Calif.

Filed Sept. 15, 1972, Ser. No. 289,760

Term of patent 14 years

Int. Cl. D13—03
U.S. Cl. D26—13 B

FIG. 1

FIG. 2

FIG. 3

FIG. 1 is a top plan view of the switch;
FIG. 2 is a side elevation view of the switch, the parts
visible in FIG. 2 being lined for transparency; and
FIG. 3 is a sectional view taken on line 3—3 of FIG. 2.
I claim:
The ornamental design for a pushbutton electric switch,
as shown.
